Primary Examiner — Sandra Morris

(57) CLAIM

The ornamental design for a bottle, as shown and described.

DESCRIPTION

FIG. 1 is a front isometric view of a bottle showing my new design;

FIG. 2 is a front elevation view of the bottle;

FIG. 3 is a top view thereof; and,

FIG. 4 is a bottom plan view of the bottle.

The cap and the bottom of the bottle shown in broken lines for illustration purposes only and form no part of the claimed design.
